UNITED STATES PATENT OFFICE.

JOHN GREER, OF GREENSBOROUGH, NORTH CAROLINA.

LUBRICATOR.

SPECIFICATION forming part of Letters Patent No. 484,195, dated October 11, 1892.

Application filed January 20, 1892. Serial No. 418,653. (No model.)

To all whom it may concern:

Be it known that I, JOHN GREER, of Greens-
borough, in the county of Guilford and State
of North Carolina, have invented certain new
5 and useful Improvements in Lubricators; and
I do hereby declare the following to be a full,
clear, and exact description of the invention,
such as will enable others skilled in the art to
which it pertains to make and use it, refer-
10 ence being had to the accompanying draw-
ings, which form part of this specification.

My invention relates to an improvement in
lubricators; and it consists of a hanger hav-
ing a rounded lower end, and which is formed
15 with a vertical oil-passage, and an oscillating
oiler having a vertical passage and a rounded
depression in its upper end, which fits the
lower end of the hanger, and a vertical spring
which is secured to the said hanger and oiler
20 and which holds them normally in line, all of
which will be more fully described hereinafter,
and more particularly referred to in the claims.

The object of my invention is to provide an
25 automatic oiler for the wrist-pins of driving-
wheels and other crank-bearings which will
lubricate the same while the said bearings are
in motion, but in which the oil-supply will be
shut off when the said bearings are at a stand-
still.

30 Referring to the accompanying drawings,
Figure 1 is an elevation of my improved lu-
bricator. Fig. 2 is an edge view of the same.
Fig. 3 is a detached view of the pivotal bolt E.

A represents a hanger, which is supported
35 on the lower end of the supply-pipe B, which
is in communication with a tank or other
source of oil-supply. This hanger is formed
with a vertical passage C, as shown, and is con-
structed with an enlarged rounded lower end.

40 D represents an oscillating oiler, which is
formed with a rounded depression in its up-
per end which fits the lower end of the hanger
B and to which the same is pivotally secured
by the pivot E. A tight swinging joint is thus
45 formed between the members A and D. The
oiler D is provided with a vertical oil-passage
F, which is forked at its upper end, as shown,
so that when the parts A D are in line the
passages formed therein will not be in line.

50 The position referred to is that shown in Fig. 1.

The extended end of the pivot E is provided
with a vertical slot, and secured therein is the
flat spring G, which extends upward to the
projection H on the hanger A, to which it is
secured. The depending end of this spring 55
is secured to the projection I on the lower end
of the oiler D, and the said spring extends be-
low the end of the said oiler, as shown. This
spring serves to hold the parts A D normally
in line, and the oiler when thrown to either 60
one side or the other will assume the said po-
sition when free to do so.

J represents the oil-cup on the driving or
crank shaft, which transmits oil to the bear-
ing. Extending upward on opposite sides of 65
this cup are the posts K, and extending across
the top of the cup and secured to these posts
is the round bar L, upon which is mounted
the roller M.

When the crank carrying the oil-cup is in 70
its highest position when revolving, the roller
M on the bar L strikes the lower end of the
depending spring and moves the oscillating
oiler to one side until the crank has passed
sufficiently far to carry the bar out of engage- 75
ment with the spring end, when the spring
will force the oiler back to its normal position.
While the oiler is thrown aside, as described
above, the vertical passages in the respective
parts A D register, and oil is thus free to pass 80
from the former through the latter and drop
into the oil-cup, as will be readily understood.
One of the forks of the passage in the oiler
serves to pass the oil when the crank is mov-
ing in one direction and the other fork passes 85
the oil when the motion is reversed. Thus it
will be seen that while the driving or other
wheel is in motion the crank carried thereby
will be constantly supplied with oil, no mat-
ter how fast the wheel may be moving, and 90
that when the said wheel is at rest the pas-
sages passing the oil, being out of register,
will stop the flow of oil until the wheel is
again set in motion.

While a flat hanger and oiler in cross-sec- 95
tion are here shown, I do not wish to limit my-
self to this particular form, as a joint resem-
bling a ball and socket may be used with
equal effect and without departing from the
spirit of my invention. In like manner the 100

oil-cup, which is here shown as oblong, may be made circular or in any other preferred form.

Having thus described my invention, I 5 claim—

1. In a lubricator, the combination of a perforated hanger formed with a rounded lower end, a perforated oiler having a rounded depression in its upper end and which is pivotally connected to the hanger, and a laterally-moving bearing which engages the oiler, vibrating the same, whereby oil is passed therethrough from the said hanger, substantially as shown and described.

15 2. In a lubricator, the combination of a perforated hanger, a perforated oiler pivoted thereto, a spring secured at its opposite ends to the hanger and oiler, respectively, and a laterally-moving bearing which engages the 20 oiler, vibrating the same, whereby oil is passed therethrough from the said hanger, substantially as shown and described.

3. In a lubricator, in combination, a perforated hanger having a rounded lower end, a 25 perforated oiler having a rounded depression in its upper end and which is pivotally connected to the said hanger, a spring having a rigid connection at its upper end with the hanger and its depending end connected to 30 the said oiler, an oil-cup mounted on the bearing which is to be lubricated, and a stop on the said cup which is adapted to engage the

depending end of the spring, and thus oscillate the oiler, substantially as shown and described.

4. In a lubricator, in combination, a perforated hanger having a rounded lower end, a perforated oiler having a depression in its upper end and which is pivotally connected to the said hanger, the said oiler being formed 40 with a vertical passage having a forked upper end, a spring secured at its opposite ends to the hanger and oiler, respectively, an oil-cup on the bearing to be lubricated, and a bar secured across the said cup which engages 45 the depending end of the spring, whereby the said conveyer is oscillated, substantially as shown and described.

5. In a lubricator, the combination, with a perforated hanger and a perforated oiler, of a 50 pivotal bolt connecting the same, the said bolt being provided with a slot in its extended end, and a spring which is secured between its ends in the said slot and which is secured at its ends to the said hanger and conveyer, 55 respectively, substantially as shown and described.

In testimony whereof I affix my signature in presence of two witnesses.

JOHN GREER.
